UNITED STATES PATENT OFFICE

LOUIS S. MICHELSON, OF LOS ANGELES, CALIFORNIA

DESIGN FOR THE TRUNKS OF A BATHING SUIT

Application filed February 10, 1932. Serial No. 42,808. Term of patent 14 years.

To all whom it may concern:

Be it known that I, LOUIS S. MICHELSON, a citizen of the United States, residing at Los Angeles, in the county of Los Angeles and State of California, have invented a new, original, and ornamental Design for Trunks of a Bathing Suit, of which the following is a specification, reference being had to the accompanying drawing, forming a part hereof.

I claim:

The ornamental design for the trunks of a bathing suit as shown.

Signed at Los Angeles, California, this 4th day of February, 1932.

LOUIS S. MICHELSON.
